CLAIM

The ornamental design for a combined electric cleaning instrument and wireless charger, as shown and described.

DESCRIPTION

FIG. 1 is a perspective view of a combined electric cleaning instrument and wireless charger, showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is an enlarged view thereof, of the portion indicated

In the drawings, the broken lines are included for the purpose of illustrating an enlarged fragmentary view indicator and portions of the article which form no part of the claimed design.

1 Claim, 8 Drawing Sheets
